UNITED STATES PATENT OFFICE.

FRANK J. WILHELM, OF CINCINNATI, OHIO, ASSIGNOR TO WILLIAM LIEBEL, OF CINCINNATI, OHIO.

DESIGN FOR A PARKING LAMP FOR AUTOMOBILES.

Application filed August 20, 1925. Serial No. 14,529. Term of patent 14 years.

To all whom it may concern:

Be it known that I, FRANK J. WILHELM, a citizen of the United States, residing at Cincinnati, in the county of Hamilton and State of Ohio, have invented a new, original, and ornamental Design for a Parking Lamp for Automobiles, of which the following is a specification, reference being had to the accompanying drawing, forming part thereof, in which—

Fig. 1 is a plan view of my new, original and ornamental design.

Fig. 2 is a side elevation of the same; and, Fig. 3 is an end elevation of the same.

I claim:

The ornamental design for a parking lamp for automobiles, substantially as shown.

FRANK J. WILHELM.
